ARCHITECTURAL SANDWICH PANEL

Verne F. Goodrich, 1410 Monroe Ave., San Mateo, Calif.

Filed Jan. 2, 1964, Ser. No. 78,002

Term of patent 14 years

(Cl. D13—1)

I claim:

The ornamental design for an architectural sandwich panel, substantially as shown.
